UNITED STATES PATENT OFFICE.

OLE P. HAMBORG AND GEORGE O. WEDING, OF MANKATO, MINNESOTA.

DESIGN FOR A BOX.

SPECIFICATION forming part of Design No. 18,248, dated April 10, 1888.

Application filed December 27, 1887. Serial No. 259,192. Term of patent 7 years.

To all whom it may concern:

Be it known that we, OLE P. HAMBORG and GEORGE O. WEDING, citizens of the United States, residing in Mankato, in the county of 5 Blue Earth and State of Minnesota, have invented and produced a new and original Design for Tobacco-Boxes, of which the following is a specification, reference being had to the accompanying drawings, forming part thereof.

10 Figure 1 is a perspective view of our design for tobacco-boxes. Fig. 2 is a design of the top or cover of this box, and Fig. 3 is a design of the back of the same.

Our design is a box of such a shape as to 15 represent, when closed, a bound book, as will appear by reference to Fig. 1 of the annexed drawings. The front or top of this box is embellished with four ornamental borders, forming a rectangular field or parallelogram. These 20 borders may be extended so as to cross each

other and form the four corners, which may be ornamented with the designs illustrated in Fig. 1. The rectangular field formed by the borders is provided with lines or borders. The back of the box is formed into a number of 25 rectangular fields by means of the ornamental lines or borders. These fields are adapted to be ornamented as shown.

What we claim is—

The herein shown and described design, consisting of a book-shaped box, the back and cover of which are provided with rectangular fields, said fields being provided with ornamental lines or borders. 30
